WRENCH

Winfred E. Drake, Bonners Ferry, Idaho; J. H. McNally, administrator of said Winfred E. Drake, deceased, assignor of fifty one-hundredths to George F. McGlocklin, Bonners Ferry, Idaho

Application December 24, 1943, Serial No. 515,473

5 Claims. (Cl. 81—100)

This invention relates to improvements in wrenches, and more particularly, in flexible jaw wrenches of the common type referred to as Stillson wrenches.

It is an important object of my invention to provide, in a wrench of the type wherein relative movable handle and shank each having a jaw, simple and easily operable clutch means for maintaining adjustment between the shank and the handle without interfering with the utility of the wrench.

Another object of the present invention is the provision, in a wrench of the type described, of wedging members and a lock therefor to clutch the shank to the jaw handle in adjusted relation in a simple operating mechanism devoid of complicated parts.

A still further object of the invention resides in the provision in a flexible jaw wrench of the type described of clutching means between the shank and handle to hold the same in adjusted relation without interfering with the flexibility of the jaws.

The foregoing objects and others ancillary thereto I prefer to accomplish as follows:

According to a preferred embodiment of my invention, I dispose upon a wrench handle, having a fixed jaw thereon, a shank guide to flexibly and pivotally mount a shank including a jaw and also clutch means between said handle and shank to retain the jaws in adjusted position. Specifically, the clutch means comprises opposed unequal wedges one of which is on the jaw shank and the other is independently mounted to abut said first wedge and the shank guide. A tapered sleeve encompasses said wedges and retains them in adjusted position to thereby retain the jaws as thus adjusted. The arrangement and inclusion of such wedge clutching means in a flexible jaw wrench is an important phase of my invention. Spring means may be included in the wrench between the handle and shank to press the two apart and it is preferable to include retractor spring means to tend to draw the sleeve toward the shank guide to maintain the wedges in clutching relation to each other. Spring means operable to move the shank longitudinally relative the handle may also be employed to facilitate the adjusting of the clutch mechanism during such times as the sleeve is removed from close encompassing position.

The novel features that I consider characteristic of my invention are set forth with particularity in the appended claims. The invention itself, however, both as to its organization and

its method of operation, together with additional objects and advantages thereof, will best be understood from the following description of specific embodiments when read in connection with the accompanying drawings in which:

Figure 1 is a side view of a preferred form of my wrench with portions broken away and others shown in section for convenience of illustration;

Figure 2 is a sectional view taken on the plane indicated as 2—2 of Figure 1;

Figure 3 is a side view of the movable jaw and its shank, the latter being partly in section;

Figure 4 is a perspective view of the wedge;

Figure 5 is a perspective view of a tapered sleeve employed in the clutch mechanism;

Figure 6 is a side view of a modified form of wrench employing the principles of my invention;

Figure 7 is a cross-sectional view taken on line 7—7 of Figure 6; and

Figure 8 is a perspective view of a filler block used in connection with my wrench.

A wrench of the flexible jaw type must have at least two totally distinct characteristics; it must be capable of rapid and secure adjustment without loss of flexibility; and it must provide a locking means for an infinite number of adjusted positions within the range of adjustment which means are simple to construct and positive in operation. Accordingly, a preferred embodiment of my invention, referring to Figures 1 through 5 of the drawings, is constituted by wrench handle 10 having fixed thereon jaw 12 and outstanding on one side a pair of flanges 14 which with filler block 16 secured therebetween by pin 18 forms the passage 20. Block 16 has groove 22 on its rear face for a purpose later to be described.

In the passage 20 is loosely mounted the shank 24 of the jaw 26 opposite to jaw 12 and movable relative thereto to grip objects. Shank 24 lies in the assembled wrench alongside the handle 10 and has a groove 28 on that face nearest the handle in which is placed the spring 30

anchored at 32 to the shank near its rear end and forwardly to hook 34 on the handle. Outwardly acting springs 36, 36 each having a cap 38, press on the inner face of shank 24 to tend to spread the same from the handle. Cheek plates 40 on the handle cover these springs and form the sides of a groove in which the shank slides in adjusting movements.

As can best be seen in Figure 3 the shank has a rearward flare on its outer edge formed by the wedge portion 42, here shown as integral with the

shank but which may obviously be separably associated therewith. The wedge portion provides the face 46 which slopes upward and rearward with relation to the axis of the handle 10.

A wedge 48 is superposed upon face 46 with its widest portion or head 49 resting in groove 22 of the shank guide. Face 50 of the wedge lies upon face 46 of the shank wedge portion. The term "unequal" is used herein to refer to the differing taper angles of the wedge and the wedge portion; i. e., one has greater taper than the other. It is to be understood that each has greater than zero angle of taper. The wedge and the wedge portion are preferably unequal so that the space they occupy between face 51 on the shank 24 and face 53 on the wedge is greater forward than that to the rear. A sleeve 52 tapered in accordance with the relative tapering of the two surfaces 51 and 53 encompasses the wedge as well as the shank and its wedge portion to maintain the two parts in frictional engagement at the various adjusted positions of the shank.

Sleeve 52 has an ear 54 to which may be attached spring 56 at one end. The other end of the spring is secured forwardly to the handle by loop member 58. This spring tends to constantly urge the sleeve 52 forward into close engagement about the wedges to lock them together.

In Figures 6 and 7 I show a slightly modified form of my invention in which the primary difference over the device above described resides in the formation of the guide means for the shank of the movable jaw. Handle 60 has jaw 62 relative to which is mounted the opposed jaw 64 on shank 66. Shank 66 has a wedge portion 68 against which is placed the wedge 70 that is retained in clutching position by sleeve 72. A spring 74 operates to urge the sleeve forwardly to gripping relation on the wedges and spring 76 tends to spread the shank 66 from handle 60. A sleeve 78 is slidably mounted on handle portion 60 and has a forward slotted ear (not shown) which encloses a pin (not shown) which limits movement of the sleeve 78. A yoke 84 between sleeve 72 and ear 80 links the two parts together. When manual pressure is applied to trigger portion 86 of the sleeve 78, the sleeve 72 is drawn rearward against the spring 74 to loosen the wedges.

The guide for the shank 66 comprises plates 90 pivotally mounted on each side of the handle on pin 92 and having block 94 which is grooved at 96 to receive a head end portion of the wedge 70. A U-shaped loop 98 loosely encloses the opposite edge of handle 60 and a leaf spring 100 secured in place by screw 102 presses the U-member and the guide plates into more lateral position and urges the shank there enclosed toward alignment with the handle 60.

Operation

With the wrench in the set position of the jaws shown in Figures 1 and 6 it will be apparent that an object may be gripped between the jaws. Turning pressure is applied to an object when the handle is swung downward or clockwise according to the views of the drawings. The wedges in Figure 1 are retained in clutching relation by the tapered sleeve 52 and the shank 24 is held against longitudinal movement which would tend to open the jaws apart. The same is true of the showing of Figure 6.

When the wrench is swung counterclockwise to the showing of the two figures of the drawings, the jaws tend to loosen on the object being gripped and the wrench may be disengaged there-

from or a new hold secured with more advantage to the mechanic.

Adjustment of the jaws is obtained by drawing the encompassing sleeve rearward from engagement about the wedges which thereby become loose permitting the springs 30 or 74 to urge the movable jaws in each case away from the handle jaws. Extension of the jaws is thus more or less automatic. Closing of them is produced by manual manipulation of the shank rearward against the action of the aforementioned springs. When the jaws are set in a desired relation, the sleeve around the wedges is released and permitted to closely engage and clamp them together to regain the clutching action.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Thus having described my invention, I claim:

- 25 1. A wrench, comprising: relatively movable opposed jaws, one of said jaws being attached to a shank adjustable with respect to said other jaw, guide means between said other jaw and adjustable shank for guiding and pivotally supporting said shank, opposed unequal wedges and a tapered sliding sleeve encompassing said shank and wedges, said sleeve being slidably relative said other jaw, said wedges being carried by said shank and guide means and said sleeve serving to limit relative movement of said wedges and of said shank with respect to said other jaw.
- 30 2. A wrench, comprising: relatively movable opposed jaws, one of said jaws being attached to a shank adjustable with respect to said other jaw, guide means between said other jaw and adjustable shank for guiding and pivotally supporting said shank, opposed unequal wedges and an encompassing tapered sleeve, said wedges and sleeve being carried by said shank and guide for limiting movement of said shank, and manually engageable means on said handle and connected to said tapered sleeve to move the same in a manner to loosen the wedges to permit movement of the shank relative the handle.
- 35 3. A wrench, comprising: a handle having secured thereto a first jaw, a second jaw, a shank secured to said second jaw, a shank guide secured to said handle for guiding and pivotally supporting said shank, spring means between said handle and shank operable to press said shank in said shank guide away from said handle, said shank having a wedge portion, a wedge unequal to said wedge portion and positioned oppositely in contact with the wedge portion of the shank,
- 40 4. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 45 5. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 50 6. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 55 7. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 60 8. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 65 9. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 70 10. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,
- 75 11. A wrench, comprising: a handle having secured thereto a first jaw, a second jaw, a shank secured to said second jaw, a shank guide secured to said handle for guiding and pivotally supporting said shank, said shank having a wedge portion, a wedge unequal to said wedge portion and positioned oppositely in contact with the wedge portion of the shank,

guide in sliding position in said groove, a tapered sleeve encompassing said shank and its wedge portion, said wedge to retain the shank in fixed longitudinal relation to said handle but without interfering with pivotal movement of the shank, and spring means urging said sleeve into clamping engagement about said wedge portion and said wedge.

5. A wrench, comprising: a handle having secured thereto a first jaw, a second jaw, a shank secured to said second jaw, a shank guide secured to said handle for guiding and pivotally support-

ing said shank, said shank having a wedge portion, a wedge unequal to said wedge portion and positioned oppositely in contact therewith, guide means between the wedge and said shank guide for guiding in and out movement of said wedge; and a tapered sliding sleeve encompassing said shank, its wedge portion, and said wedge to retain the shank in fixed longitudinal relation to said handle but without interfering with pivotal movement of the shank and said second jaw.

WINFRED E. DRAKE.
